REVOLVING GARMENT CARRIER

Carl Krauss, Chicago, Ill., assignor to Garden
City Plating & Mfg. Co., Inc., a corporation of
Illinois

Application July 18, 1938, Serial No. 219,736

6 Claims. (Cl. 312—133)

This invention relates to improvements in revolving garment carriers.

The revolving garment carrier of the present invention is intended for use in a display cabinet or closet, or other limited area for the purpose of providing increased garment carrying means, and is constructed and arranged to enable the ready inspection or removal of the garments carried by the hanging rods. In accordance with my present invention I provide a garment carrier having a rotatable shaft which carries a pair of parallel, spaced garment hanging rods. The garment carrier is mounted on rollers to permit movement to a position wholly within the cabinet or closet, or to a position at the front end or entrance of the cabinet or closet. Means are provided to lock the shaft and associated hanging rods to prevent rotation thereof when the carrier is wholly within the cabinet or closet and to unlock the shaft and associated hanging rods when the carrier is at the entrance of the cabinet or closet and thereby permit a reversal of the carrier to enable the ready inspection and removal of the garments from the carrier by a person outside the cabinet or closet. The above purposes are achieved by the garment carrier embodying my invention which is illustrated in the accompanying drawings.

The rotatable garment carrier embodying the present invention is simple in design, construction and assembly and relatively inexpensive to manufacture.

The invention possesses many other advantages which may be made more easily apparent from a consideration of the embodiment shown in the drawings. This embodiment will be described in detail to illustrate the invention; but it is to be understood that the invention is not limited to the details shown and described, except as set forth in the appended claims.

The invention is illustrated in the accompanying drawings wherein:

Figure 1 is a perspective view of a revolving garment carrier embodying my invention;

Figure 2 is a vertical sectional view longitudinally through the carrier base and base frame of the garment carrier of Figure 1 and showing the carrier base in the rear position on the base frame with the shaft in locked position;

Figure 3 is a sectional view similar to Figure 2 with the carrier base in the forward position on the base frame and showing the shaft in unlocked position;

Figure 4 is a horizontal sectional view of the

carrier base and base frame on the line 4—4 of Figure 2 showing the base frame in plan;

Figure 5 is a transverse sectional view on the line 5—5 of Figure 2 showing the details of construction of the base frame and the associated locking means for the carrier base;

Figure 6 is a fragmentary detail sectional view on line 6—6 of Figure 4, showing the construction of the locking means for the carrier base; and

Figure 7 is a fragmentary perspective view of self-centering mechanism for the shaft.

In the drawings, referring particularly to Figure 1, there is shown a rotatable garment carrier embodying my invention. The garment carrier comprises a base frame, designated as a whole by the numeral 10, which is adapted to be positioned in and rest on or be secured to the floor of a display cabinet or closet (not shown) or in any other confined area. Carrier base 11 of the garment carrier is supported on flanged rollers 12 which are adapted to run in tracks formed, as hereinafter described, in the base frame. Rotatable shaft 13 extends through the carrier base 11 and has secured to the upper end thereof a hanging rack 14 adapted to be rotated therewith. A pair of spaced garment hanging rods 15 is secured to rack 14, and end garment guards 16 are secured to and extend between the garment hanging rods.

The base frame 10 is of rectangular shape and is formed of a pair of opposed channel irons 17 and 18 which form the sides of the base frame, and end plates 19 and 20. The bottom sides of the opposed channel irons 17 and 18 form a runway or pair of tracks 10a for the wheels 12 on which carrier base 11 is mounted as hereinafter described.

Carrier base 11 is formed of a base plate 21 having a center opening and a vertical hollow extension or boss 22 (Figures 2 and 3) secured to or formed integrally with said base plate as by the angular connecting and reinforcing webs 23. The opening in the boss or extension 22 is aligned with the opening in the base plate 21 to permit the passage therethrough of shaft 13. The bottom portion of boss 22 adjacent the base plate 21 is provided with a cut out portion or opening 24 for a purpose to be hereinafter described. If desired, boss 22 and base plate 21 may be formed separately and secured together as by the webs 23.

To the base plate 21 of the carrier base 11 are secured the axles 25 and 26 on which the wheels 12 are attached to permit of a to and fro movement of the carrier base 11 and its associated

parts on the tracks in the base frame 10. The base frame 10 is intended to extend into a cabinet or closet with the front end 19 positioned parallel to and closely adjacent to the entrance to the cabinet or closet. Thus, carrier base 11 and its associated hanging rods carrying the garments may be rolled back in the base frame until the rear end of the base plate 21 abuts the rear end 20, in which position the garments are positioned wholly within the cabinet; or the carrier base 11 may be pulled forward until the front end of base plate 21 abuts front end 19, in which position the garments on hanging rods 15 are positioned adjacent to the entrance of the cabinet. When the carrier base 11 is pushed back in the base frame against rear end 20, the front wheels 12 are engaged and locked by the spring clamps 27 to prevent unassisted movement of the carrier base in the base frame. When the carrier base 11 is pulled forward in the base frame against front end 19, the rear wheels 12 are engaged and locked by the spring clamp 27 to prevent unassisted return movement of the carrier base in the base frame. These spring clamps 27 are formed of a suitable resilient spring-like metal or metal alloy and as shown in Figures 1, 4, 5, and 6, may be secured to the top sides of the channel irons 17 and 18 substantially centrally thereof. They extend inwardly of the base frame and are provided with a downwardly extending bent clip 28 which is adapted to press against the flange on rollers 12 to lock the wheels frictionally as shown in Figure 5 and thereby prevent unassisted movement of the carrier base frame as described above.

The garment carrier is provided with an automatic self-centering shaft mechanism, shown in perspective in Figure 7, which is positioned in the central opening in the base plate 21, as shown in Figures 2 and 3. This mechanism is designed to cooperate with shaft 13 to cause the shaft, after rotation, to come to rest automatically in the desired position shown in Figure 1 with the hanging rods 15 on rack 14 extending transversely to the base frame.

The self-centering mechanism comprises an annular cam member, designated as a whole by the numeral 29, and a dumb-roller assembly 30. Cam member 29 is mounted on or formed integrally with a plate 31 mounted on the under side of carrier base plate 21 and having a central opening of a size sufficient to permit shaft 13 to pass therethrough. The annular cam member 29 is provided on its upper surface with a cam surface having two identical portions 33 and 34 on opposite sides of the cam surface upcurved at their meeting points to form raised knife edges 35 and 36 diametrically opposite each. On each identical portion and perpendicular to the knife edges are low spots 38 and 39 to provide a stable rest position. Dumb-bell roller assembly 30 comprises an axle 41 passing through a slot or opening 44 formed in shaft 13, and having cam rollers 42 and 43 rotatably mounted thereon.

To assemble the garment carrier with the self-centering mechanism, cam number 29 is first introduced into the opening in base plate 21 and arranged in the opening so that the knife edges 35 and 36 on the cam surface thereof are positioned in a direction transverse to the length of the base frame; the low points 38 and 39 thereby occupying a position parallel thereto. Base plate 31 is then bolted, screwed or otherwise secured to the bottom of plate 21. The dumb-bell roller 30 is now introduced through opening 24 in boss 22 and

positioned on cam 29 with the rollers 42 and 43 resting on the flat portions 38 and 39 of the cam surface. Shaft 13, having a slot 44 at its lower end, is then threaded through the opening in boss 22 and caused to straddle and be supported at the top of slot 44 on the axle 41 of the dumb-bell roller 30. The bifurcated end of shaft 13 extends through the cam member 29 to a position slightly below plate 31. The hanger rack 14 carrying the hanging rods 15 is now positioned on the shaft and secured thereto at any desired height, as by the set screw 45, with the hanging rods parallel to the plane passing through knife edges 35 and 36 on cam member 29.

The shaft 13 may be locked against rotation by a locking lever 46 fulcrumed as at 47 to lugs or ears 48 extending downwardly from base plate 21 between the front end and middle portion thereof. The rearwardly extending arm of lever 46 may be caused to extend into end slot 44 of shaft 13 to lock the shaft against rotation as shown in Fig. 2. The other arm of lever 46 extends outwardly a short distance beyond the front end of base plate 21 and is provided at its free end with a pair of transversely extending cam rollers 49. Cam rollers 49 are adapted to coat with an inclined cam guide 50 secured to front end 19 of the base frame to unlock shaft 13 or to lock it in a manner to be described. Cam guide 50 functions as a double acting cam and as shown in Figures 2, 3, and 4, is provided with an upwardly sloping cam surface 51 on which cam rollers 49 are adapted to ride when the carrier is pulled forward and an over-hanging centrally slotted member having downwardly extending fingers 52. The under surfaces of fingers 52 are substantially parallel and opposed to cam surface 51 and provide cam surfaces against which cam rollers 49 bear to effect locking of shaft 13 when the carrier is pushed back.

The operation of the device is as follows: When the garment carrier is in the position shown in Figure 2, it is wholly within the cabinet or closet and the shaft and associated rack are locked against rotation. On pulling the carrier forward in the base frame to the position shown in Fig. 3, the cam rollers 49 strike cam surface 51 and ride upwardly thereon, thereby raising the outwardly extending arm of lever 46 and lowering the rearwardly extending arm to remove it from slot 44 in shaft 13, thereby permitting rotation of the latter. If it is desired to reverse the position of hanging rods 15, the shaft is rotated. The shaft will then come to rest in the desired position by the action of the self-centering mechanism hereinabove described. To return the garment carrier to the position shown in Fig. 2, the carrier is pushed back and the cam surfaces of fingers 52 bear against cam rollers 49 to depress the forward end of lever 46 and cause the rear end thereof to move into slot 44 to lock the shaft. The short arm of lever 46 is preferably slightly heavier than the longer arm and thus unassisted unlocking of shaft 13 is prevented. The slot is provided in the overhanging member of cam guide 50 to provide clearance for the arm of the lever carrying rollers 49, and thereby enable the latter to ride up to the top of sloping cam surface 51 as shown in Figure 3 and thereby also permit the front end of plate 21 to approach closely to end 19 of the base frame.

I claim:

1. In a rotatable garment carrier, a base frame having tracks and a carrier member mounted on rollers movable back and forth on said tracks,

a shaft rotatably mounted in said carrier member and having a slotted end extending below it, means for locking said shaft against rotation comprising a lever fulcrumed to the bottom of said carrier member adjacent the forward end thereof, said lever having an arm extending rearwardly into said slot and an arm extending outwardly from the carrier member, and a double acting cam at the forward end of said base frame, the arm of the lever extending outwardly from the carrier member having a member at the end thereof adapted on forward movement of the carrier member to coact with said cam to cause the rearwardly extending arm of the lever to move out of the slot to unlock the shaft, and adapted on rearward movement to coact with said cam to push said rearwardly extending arm into the slot to lock the shaft.

2. In a rotatable garment carrier, a base frame having tracks and a carrier member mounted on a pair of front and back rollers adapted to move back and forth on said tracks, a shaft rotatably mounted in said carrier member and having a slotted end extending below it, means for locking said shaft against rotation comprising a lever fulcrumed to the bottom of said carrier member adjacent the forward end thereof, said lever having an arm extending rearwardly into said slot and an arm extending outwardly from the carrier, and a double acting cam at the forward end of said base frame, the arm of the lever extending outwardly from the carrier member having a member at the end thereof adapted on forward movement of the carrier member to coact with said double acting cam to cause the rearwardly extending arm of the lever to move out of the slot to unlock the shaft, and adapted on rearward movement to coact with said double acting cam to urge said rearwardly extending arm to move into the slot to lock the shaft, and a pair of spring clips on opposite sides of said base frame adapted to engage frictionally the front wheels on which said carrier member is mounted when the carrier member is in the rearward position in said base frame and to engage frictionally the rear wheels when the carrier member is in the forward position in said base frame whereby unassisted movement of the carrier member when in its rear and forward positions is prevented.

3. In a rotatable garment carrier, a base frame having tracks and a carrier member mounted on rollers adapted to move back and forth on said tracks, a shaft rotatably mounted in said carrier member and having a slotted end extending beneath it, self-centering means associated with the shaft to effect centering thereof after rotation comprising an annular cam member secured to the carrier member and through which the shaft extends, said annular cam member having opposed identical cam surfaces, a pin extending through the slot and having a pair of rollers at the extremities thereof riding on said pair of opposed cam surfaces, said pin supporting said shaft in said carrier member, means for locking said shaft against rotation comprising a lever fulcrumed to the bottom of said carrier member adjacent the forward end thereof, said lever having an arm extending rearwardly into said slot and an arm extending outwardly from the carrier member, and a double acting cam at the forward end of said base frame, the arm of the lever extending outwardly from the carrier member having a cam member at the end thereof adapted on forward movement of the carrier member to coact with said double acting cam to cause the rearwardly extending arm of the lever to move out of the slot to unlock the shaft, and adapted on rearward movement to coact with said double acting cam to cause said rearwardly extending arm to move into the slot to lock the shaft.

the carrier member to coact with said double acting cam to cause the rearwardly extending arm of the lever to move out of the slot to unlock the shaft, and adapted on rearward movement to coact with said double acting cam to cause said rearwardly extending arm to move into the slot to lock the shaft.

4. In a rotatable garment carrier, a base frame and a carrier member adapted to move back and forth therein, a shaft, means for rotatably mounting said shaft in said carrier member, said means including means for causing said shaft to assume a definite rest position, locking means carried by said carrier member and adapted to coact with said shaft only while the shaft is in rest position for locking the shaft against rotation and means adapted on forward movement of the carrier member to the front part of the base frame to coact with said locking means to unlock the shaft, said last-named means being also adapted on rearward movement of the carrier to coact with said locking means to lock the shaft.

5. In a rotatable garment carrier, a base frame having tracks and a carrier member mounted on rollers and adapted to be moved back and forth on said tracks, a shaft rotatably mounted in said carrier member and having a slotted end extending below it, means for locking said shaft against rotation comprising a lever fulcrumed to the bottom of said carrier member adjacent the forward end thereof, said lever having an arm extending rearwardly into said slot and an arm extending outwardly from said carrier, said outwardly extending arm having a pair of spaced cam rollers at the end thereof, and a double acting cam at the forward end of said base frame, said double acting cam comprising an upwardly sloping cam surface on which said cam rollers are adapted to ride on forward movement of the carrier member to unlock the shaft and an overhanging slotted member having a pair of fingers, the under surfaces of which are parallel and opposed to said upwardly sloping surface whereby on rearward movement of the carrier said cam rollers bear against the under surfaces of said fingers to lock the shaft.

6. In a rotatable garment carrier, a base frame and a carrier member adapted to move back and forth therein, a shaft having a slotted end, means for rotatably mounting said shaft in said carrier member with the slotted end extending below it, said means including means for causing said shaft to assume a definite rest position and means adapted to coact with said shaft only while the shaft is in rest position for locking the shaft against rotation, said last named means comprising a lever fulcrumed to the bottom of said carrier member adjacent the forward end thereof, said lever having an arm extending rearwardly into said slot and an arm extending outwardly from said carrier member, and a double acting cam at the forward end of said base frame, the arm of the lever extending outwardly from the carrier member having a cam member at the end thereof adapted on forward movement of the carrier member to coact with said double acting cam to cause the rearwardly extending arm of the lever to move out of the slot to unlock the shaft, and adapted on rearward movement to coact with said double acting cam to cause said rearwardly extending arm to move into the slot to lock the shaft.
